UNITED STATES PATENT OFFICE.

DE WITT W. BUCHANAN, OF CHICAGO, ILLINOIS.

METHOD OF AND APPARATUS FOR HANDLING COAL.

1,201,685.

Specification of Letters Patent. Patented Oct. 17, 1916.

Application filed February 12, 1915. Serial No. 7,766.

To all whom it may concern:

Be it known that I, DE WITT W. BUCHANAN, a citizen of the United States, residing at Chicago, in the county of Cook and State of Illinois, have invented a new and useful Improvement in Methods of and Apparatus for Handling Coal, of which the following is a specification:

My invention relates to improvements in the art of handling coal.

More particularly, the invention is concerned with a method and means for grading and distributing freshly-mined coal, for loading the distributed coal into cars, for automatically re-grading the coal during such loading operation, and for re-distributing any coal rejected by the loading apparatus.

With the above and other objects in view, I have provided the method of and apparatus for handling coal, which is specifically described in the following specification and illustrated by the accompanying drawings, in which—

Figure 1 is a side elevation of the re-grading and loading machine of my invention, and showing the relation of this machine to the storage bin and to the car which is to be loaded; Fig. 2 is a section on line 2 of Fig. 1; Fig. 3 is a section on the line 3 of Fig. 1; Fig. 4 is a section on the line 4 of Fig. 2; Fig. 5 is an enlarged section on the line 5 of Fig. 1; Fig. 6 is an enlarged section through the horizontal re-distributing conveyer and through the loading chute therefor; Fig. 7 is a diagrammatic view of the entire coal-handling plant; Fig. 8 is an enlarged elevation of a portion of the distributing conveyer and the means for discharging coal rejected by the loading machine onto the same, and Fig. 9 is an end elevation of the apparatus shown in Fig. 8, the inclined conveyer being shown in section.

For the purpose of making the description of my invention more readily understood, it may be best to first refer to the diagrammatic view of the entire coal-handling plant which is represented by Fig. 7. In this figure of the drawing, the numeral 10 designates the shaft-head of a coal mine. This head will contain suitable means for elevating coal from the mine, crushing the freshly-mined coal, and discharging the coal thus crushed upon the upper surface of the in-

clined conveyer 11. This conveyer, traveling in the direction of the arrow, will elevate the mixture of various sizes and grades of coal and slate and will discharge the mixture at the top of the storage house 12, within which is located suitable apparatus for separating the slate from the coal and for grading or sorting the coal according to the size of the lumps. Commonly, about six grades or sizes are recognized as standard market grades, and the storage house 12 is therefore provided with at least six, and usually more, separate bins, here designated 13, each bin being designed to contain only its own special size or grade of coal. The bins 13 will each be provided, in common practice, with a hopper-bottom having a suitable outlet gate 14 positioned at some distance above the ground level to permit a railroad car 15, which runs on tracks beneath the row of bins, to be filled by gravity directly from the bins.

In handling and distributing coal in the manner and with an apparatus of the general form of that described, I find that the distributing and grading processes within the storage house 12 cannot be relied upon to effectively "size" the coal, so that each bin will contain only the grade of coal which it is nominally said to contain. Without discussing the reasons for this in any great detail, it may be stated that in general it is customary to separate the slate from the coal after the latter has been graded, and that in this slate-separating process and by traveling through the chutes, the screens, etc., and dropping into the bins, a considerable fraction of the coal becomes broken up, so that a bin which, for instance, should nominally contain the grade of coal known as furnace coal, that is, coal having lumps approximately six inches in greatest diameter and three inches in smallest diameter will be found to contain a considerable proportion of very much smaller pieces, which are formed by the breaking up of the larger lumps in the distributing and slate-removal processes.

It is the specific object of my invention therefore to provide a means adapted to be interposed between the bins 13 and the coal car 15 for again grading the coal and rejecting all lumps which should not properly be found in the coal of the grade desired.

This object I accomplish by a combined loading and grading apparatus, mounted to travel beneath a row of bins and receive coal from any one of the latter, separate out the improperly sized lumps and discharge the re-graded coal into the car.

It is a further object of the invention to provide this loading machine with a means for discharging the rejected coal onto suitable conveyers by which it may be transported to the top of the storage house and again sorted or graded.

In Fig. 7, the loading and re-grading machine is designated by the numeral 16 and is mounted to travel upon a track 17 parallel to and beneath the row of hoppers 13. The rejected coal is discharged by the loading machine 16 onto a conveyer belt 18, by the latter is carried to a second conveyer belt 19, and finally delivered through the chute 20 onto the conveyer 11 on which it mixes with the freshly-mined coal and is carried to the top of the storage house 12 to be again graded and distributed to the bins 13. The apparatus shown schematically in Fig. 7 therefore operates in a continuous manner, and without waste, to grade and distribute the coal, to re-grade the coal prior to loading the same, and to re-grade and re-distribute the coal rejected during the loading operation. By this apparatus and by this method of handling the coal, I am therefore able to insure the highest degree of uniformity of the loaded coal, and this, without substantial additions to the ordinary and well-known forms of coal-handling apparatus and without increasing the cost of handling the coal to any great extent.

The loading and re-grading machine which is interposed between the hoppers 13 and the coal-car 15, is shown in detail in Figs. 1 to 5 of the drawings. From these figures, it will be seen that the track 17, on which the loading machine travels, is carried by beams 21 supported upon columns 22, which form a part of the structure of the storage house 12. The loading apparatus *per se*, comprises a substantial rectangular frame, designated 23 as a whole by 23, and consisting of transverse members 24 and 25 at the front and rear, respectively, and longitudinal members 26, which lie upon and are secured to the transverse members 24, 25. Front and rear axles 27, 28, respectively, are supported on the frame by bearings 29 and carry at their ends wheels 30 having grooved treads which embrace the tread-portions of the track sections 17. The front axle 27 is adapted to be driven as by a motor 31 and through a suitable reducing gear-train 32 and a driving gear 33, keyed upon the axle, so that the loading machine may be propelled along the track 17. Mounted between the side longitudinal members 26 of the frame are longi-

tudinal I-beams 34, which rest upon and are secured to the front and rear transverse frame members 24, 25, respectively, these longitudinal members extending forward of the frame proper for the purpose of supporting the loading chute. This chute, designated 36 in the drawing, is carried by a shaft 35 journalled in bearings 37 mounted upon the upper surfaces of the I-beams 34, and has its front end supported by cables 38 which are wound upon a shaft 39 carried in brackets 40 at the outer or front ends of the I-beams 34 and operable through a hand-wheel 41, a third bearing bracket 42 supporting the end of the shaft 39 adjacent 80 the hand-wheel. Suitable ratchet mechanism, not shown, will be provided to hold the shaft 39 against rotation and permit of maintaining the chute 36 in any adjusted angular position.

Carried by the frame 23 of my traveling loading machine, and adapted to receive coal from the hopper 13 and discharge the same into the loading chute 36, is a shaking screen 43. This screen is carried on transverse angle sections 44, which are mounted upon flexible vertical supports 45. The supports are preferably constructed of ash or other tough and resilient wood, and are fixedly secured at their lower ends by a sub-frame depending from the main frame 23 and lying between the tracks 17. As best shown in Fig. 4 the sub-frame consists of longitudinal members 46 united by gusset-plates 47 to outwardly inclining struts 48 and inwardly 100 inclining struts 49, which are secured to the lower faces of the longitudinal frame members 26. By means of these inclined struts the sub-frame forms a rigid structure in which the lower ends of the flexible supports 45 may be mounted. The shaking screen 43 is adapted to be reciprocated by a pair of flexible connecting rods 50 having their ends bolted or otherwise fixed to the screen frame and driven from eccentrics 52 carried by a transverse shaft 53 which is journalled, as at 54, upon the longitudinal I-beams 34. The shaft 53 is driven by the gear-train 55 from an electric motor 56 mounted upon the rear end of one of the longitudinal frame members 26. A second pair of eccentrics 57, carried by the shaft 53 and mounted outside of the eccentrics 52 and at an angle of 180° to the latter, carry a second pair of connecting rods 58, the free ends 59 of which are journalled, as at 60, upon projecting pintles of a counterbalance roll 61 (see Fig. 4), which is adapted to reciprocate across the surface of a table 62 resting upon the transverse frame member 24 at its front end and upon a channel section 63 parallel to the frame member 24 at its rear end. The weight of the counterbalance roll is preferably exactly equal to that of the screen 43 together with 136

the weight of the coal carried by the screen in the normal operation of the machine.

As shown in the drawing, the screen 43 inclines forwardly at an angle of about 10° to 20°, which, in connection with the shaking or reciprocating movement imparted to the screen by the connecting rods 50, is sufficient to cause the coal to feed slowly downward and into the chute 36. For the purpose of separating from the passing stream of coal, as it moves over the screen 43, any lumps smaller than those proper for the particular grade with which the car is being filled, the screen is provided with a perforated bottom 64, which is divided into three sections 65, 66 and 67. The perforations or meshes of the section 65 will be of the largest size, the perforations of 66 will be next largest, and the perforations of 67 will be the smallest. At the dividing line between the screen section 65 and the section 66, the side-walls 68 of the screen frame will be provided with channels 69 in which a tail-gate may be mounted to separate the two sections of the screen. Above the screen section 67 and lying across the top of the side wall 68 of the screen, there is a fourth screen member 70 having perforations still smaller than those of the screen 67. The screen member 70 is provided with an upstanding rim 71, which embraces the back and both sides of the screen. In its normal position, the screen member 70 rests upon ribs 72 carried by the side walls 68 of the main screen 43, and by swinging the screen member 70 about its pivot it may describe the path shown in dotted lines in Fig. 4 until it comes to rest above the screen section 68, in which position its rear wall 73 forms a tail-gate to separate the screen sections 66 and 67.

To receive any coal which passes through the meshes of the screens, I provide chutes 74 and 75 convergently inclined and discharging at their lower ends into the housing 76 of a transverse screw conveyer 77. The chute 74 is secured to the frame of the loading machine, being carried by brackets 78 mounted thereon. The chute 75, however, is fixed at its upper end to the frame of the screen 43 so as to be reciprocated with the latter. This I find desirable in order that any coal dropping into the chute 75 which, as shown, has a very slight inclination horizontally, may be effectively fed downward into the conveyer housing. The screw conveyer 77 is mounted upon a shaft 79, the outer end of which carries a sprocket wheel 80 driven by a chain 81 from a similar sprocket 82 mounted on the shaft 53 (see Fig. 3). The conveyer housing passes transversely of the frame of the loading machine and on one end is extended beyond the track 17 to discharge into a stationary inclined chute 83 which leads to the horizontal

conveyer 18 (see Fig. 6). This latter conveyer may be mounted beneath a platform or runway 84 extending along parallel to the track 17.

The operation of my improved loading machine, when used for the purpose of grading and re-distributing coal in the manner contemplated by my invention, is as follows: The coal is lifted from the mine, or obtained from some other source of supply, being at that time in the form of a crushed mass of mixed coal and slate of varying sized lumps, and in this form is discharged upon the bottom of the inclined conveyer 11. By the latter, it is carried upward to the top of the storage house 12 and in its passage downward through this house, it is sorted, or graded into lumps of various sizes, the slate is removed, and the various grades of coal then distributed to their proper bins 13. This process may be carried on by any one of several known methods, which are not described in detail since they form no part of my improvement. In connection with this part of the coal-handling apparatus, it need only be stated that the grading or sorting of the coal as carried out within the storage house 12, though conducted in accordance with the most efficient methods, is usually not a perfect operation, as has been pointed out. Even though the initial sorting may have been perfect, however, subsequent handling of the coal, removal of the slate therefrom, and distribution into the bins will, in general, produce some breaking up of the larger lumps, so that a bin nominally said to contain furnace coal for instance, will be found to have intermixed therewith a certain proportion of smaller sized lumps, which should be properly graded as stove, egg, pea, or some other smaller sized coal. It is the immediate object of my invention to provide means by which this imperfect grading may be corrected at the time the coal is loaded, to the end that only perfectly sized and graded coal will reach the car 15. This result is accomplished by my loading machine in the following manner: The driving motor 31 of the machine will be energized to propel the latter to a position beneath the proper bin 13 and the coal car 15 will then be pulled under the discharge chute 36 of the loading machine. It should be noted at this point that chutes 83, discharging upon the horizontal conveyer 18, will be located at proper positions to receive the discharge of the horizontal conveyer from the loading machine when the latter is in position beneath any one of the hoppers 13. The hopper-gate 14 will now be opened (a suitable hand-wheel 14', which lies in a position to be reached from the runway 84 being connected to operate this gate), and simultaneously the electric motor 56 will be started and

through it gear connections will drive the shaft 53. The rotation of the eccentrics 52, mounted on the shaft 53, will impart to the flexible connecting rods 50 a reciprocating and "whipping" motion. These connecting rods are preferably of ash wood, reduced at their center portions as shown, to produce the necessary flexibility, and the so-called "whipping" of the screen 43 will be accentuated by the flexible supports 45 on which the screen is mounted. I find that this species of "whipping" reciprocation, obtained by the use of flexible or resilient screen supports and flexible connecting rods rigidly attached to the screen, is peculiarly desirable and efficient in effecting the screening of the coal. The stream of coal discharging through the open gate 14 and onto the screen bottom will move slowly downward across the bottom, and, due to the vibratory motion of the screen, any lumps which are below the standard size will pass through the meshes of the screen onto the chutes 74 or 75, and from the latter into the conveyer 76. By this conveyer such rejected coal will be fed outwardly, delivered to the stationary chute 83, and from the latter onto the horizontal conveyer 18. The main body of the coal passes slowly downward across the face of the screen into the chute 36 and from the latter is discharged into the coal-car 15.

It may be noted at this point that the screen 43 must be caused to vibrate or "whip" at a considerable speed, for such vibrations to be most efficient in screening and separating the coal, and at such high speed of vibration, there is a pronounced and objectionable shaking movement of the loading machine as a whole. This, I effectively overcome by means of the counterbalance roll 61 and connecting rods 58. These connecting rods are carried by eccentrics 57 spaced 180° from the eccentrics 52, so that the movement of the rods 58 is at all times equal and opposite to the movement of the rods 50, and since the counterbalance roll is of the same weight as the screen and the coal contained therein, all forces of reciprocation become perfectly balanced, and the objectional vibration of the apparatus as a whole, is avoided. This feature is of peculiar importance, since it is not desirable to make the loading machine any stronger or heavier than necessary, or to anchor it to the tracks when operating, and were it not for the provision of the counterbalancing roll, it would either be necessary to construct the machine very heavily and substantially to withstand the vibration of the screen, or to anchor it securely to the tracks while in operation.

Such of the coal discharged from the bin 13 as was below standard size, will be rejected by the machine in the manner de-

scribed and delivered to the horizontal conveyer 18, and from the latter will be transported to the conveyer 19, thence to the discharge spout 20 and onto the elevating conveyer 11 where it will mix with the incoming stream of coal on its way to the top of the storage house, and it will therefore be seen that such rejected coal is not wasted but on the other hand is conveniently and automatically returned to the top of the storage house to be again distributed to its proper bins.

As stated in the introduction to this specification, the bins 13 will contain various sizes of coal and it is therefore clear that a single screen 43 having the same mesh or size of perforations throughout its surface would not be desirable for the grading of the different sizes of coal. With this in mind I have provided the four screens 65, 66, 67 and 70, arranged in the manner shown. When the bin containing the largest size coal is discharging upon the screen of the loading machine, the latter will be positioned to receive the discharge upon the screen 65 containing the largest size perforations. It is obvious that any coal which will not pass through the perforations of the screen 65 will flow continuously over the second and third screens 66, 67, without being affected thereby and in the same manner as if these screens formed an imperforate chute. If a bin containing a size of coal smaller in one dimension than the meshes of the screen 65 is to be emptied, a tail-gate will be placed in the guide-way 69 separating the screens 65 and 66 and the loading machine will then be so positioned with relation to the hopper that the coal will discharge from the latter directly onto the screen 66, and thence downwardly over the screen 67 into the coal car, as usual. If a still smaller size of coal is to be graded, the superposed screen 70 will be turned back, as indicated by the dotted are in Fig. 4, to lie above the screen 68, the end wall 73 of the screen 70 then forming a tail-gate for the screen 67. The loading machine will then be so positioned with relation to the hopper as to receive the discharge of coal directly upon the screen 67. If the very smallest size of coal is to be graded, the superposed screen 70 will be positioned as shown in full lines in Fig. 4, and the loading machine so placed with reference to the hopper as to receive the discharge of coal therefrom directly upon the screen 70. It is quite obvious that any coal small enough to pass through the meshes of the fine screen 70, will also pass through the larger apertures of the screen 67 beneath the screen 70, and thence to the chute 75. By the use of screens of four sizes, I find it possible to effectively grade at least six different sizes of coal. If the hoppers 13 contained more or less grades or sizes of coal, it will be ob-

vious that the screen 43 may be further subdivided or some of its divisions may be left out, as the case may be.

The ultimate result designed to be accomplished by my invention is the handling of coal in such a manner as to insure the delivery to the coal-car of a perfectly sized or graded product, free of slack or dust and broken fragments. By my invention this result is accomplished without substantially altering the operation of the coal-handling plant, as a whole, and without costly additions to the same. The coal-loading machine interposed between the hoppers and the coal cars, when constructed in accordance with my invention, will operate perfectly in combination with the system, as a whole, to accomplish the ultimate result aimed at in my invention in a simple and efficient manner. I regard it as an especially advantageous feature of my invention that I am able to make use of the existing coal-elevating, separating, and distributing apparatus in the simplest manner, to provide for returning the coal rejected by my loading machine to the storage house to be distributed therein by the existing machinery into its proper bins.

While I have shown and described in considerable detail the exact manner in which I prefer to carry out the handling of coal according to my invention and have illustrated and described a specific apparatus adapted to perform the results aimed at by my invention in the simplest manner, it is to be understood that I do not regard my invention as limited to these details of operation or construction, except in so far as they are included within the terms of the following claims, in which it is my intention to claim all novelty inherent in the invention in as broad a manner as is permissible in view of the prior art.

What I claim is:

45 1. The method of handling coal which consists of the following steps; continuously supplying ungraded coal, grading such supply according to the sizes of the lumps, distributing the various grades to receptacles, discharging the graded coal from the receptacles and simultaneously re-grading to separate out lumps of smaller size, returning such rejected coal to the ungraded supply and then grading out said smaller lumps and combining the same with corresponding small graded coal.

2. In coal-handling apparatus a storage house, means for supplying ungraded coal to the storage house, a plurality of bins therein adapted to contain different sizes of coal, means for grading the coal according to the sizes thereof and distributing it to the said bins, means adapted to receive the coal directly as it is discharged from the bins and to re-grade it to separate out lumps of

smaller size, and means for directly discharging said regraded coal to the source of supply of ungraded coal whence it is regraded therewith.

3. In a coal-handling apparatus, a storage house, means for supplying ungraded coal thereto, a plurality of bins therein adapted to contain coal of different sizes, means for grading the coal according to the size of the lumps and distributing the same to the said bins, means to receive the coal directly from the said bins, and to regrade it to separate out lumps of smaller size, means for directly discharging the re-graded coal and means for returning the rejected coal to the first-named supply means where it is regraded.

4. In apparatus for handling coal and, in combination, a storage house, a conveyer for supplying ungraded coal to the top of said house, a plurality of bins located in the lower portion of said house, means for grading the coal according to the size of the lumps thereof and for distributing the graded coal to said bins, a movable grading machine adapted to be placed in operative position with relation to the discharge aperture of any selected bin, means carried by said machine for re-grading coal and separating out lumps of smaller size, means for discharging the re-graded coal through one outlet, means for discharging the rejected coal through another outlet, and a conveyer in operative relation to the said second-named outlet and adapted to transport the rejected coal to said first conveyer, for the purpose described.

5. In coal-handling apparatus and, in combination, a plurality of bins mounted in a single row and having elevated discharge outlets, a track lying parallel to and below the discharge outlet of the row of bins, a loading and grading machine mounted to travel on said track for positioning in operative relation to any one of the said outlets, means thereon for discharging graded coal, means thereon for separately discharging rejected coal and means for carrying said rejected coal back to the bins containing coal of corresponding size.

6. In coal-handling apparatus and, in combination, a plurality of bins having graded coal mounted in a single row and having elevated outlet apertures, a track lying parallel to and below the outlet apertures of the row of bins, a loading machine adapted to travel upon the track and to be positioned beneath any selected outlet aperture, means carried by the said machine for grading coal discharged from the bins, means for discharging graded coal, means for separately discharging rejected coal, and means operatively related to said last-named means for transporting rejected coal.

back to the said bins containing coal of corresponding size.

7. In coal-handling apparatus and, in combination, a plurality of bins mounted in a single row and having elevated outlet apertures, a track lying parallel to and below the outlet apertures of the row of bins, a loading machine mounted to travel upon the said track for positioning beneath any selected outlet aperture to receive the discharge therefrom by gravity, a shaking screen carried by the said machine and adapted to receive the gravity discharge of coal, means for discharging coal which passes over the screen, and means for separately discharging coal which passes through the screen and returning the same to the bins containing coal of corresponding size.

8. In a coal-handling apparatus and, in combination, a plurality of bins mounted in a single row and having elevated outlet apertures, means for grading and distributing run of the mine coal thereto, a track lying parallel to and beneath the apertures of the row of bins, a loading machine adapted to travel upon the said track for positioning beneath any selected outlet aperture, a screen carried by the said machine and positioned to receive the gravity discharge of coal from said outlet aperture, means for moving the screen, means for receiving the discharging coal which passes over the screen, and separate means for receiving the discharging coal which passes through the screen and returning the same with the run of the mine coal.

9. In apparatus for handling coal and, in combination, a plurality of bins mounted in a single row and having elevated outlet apertures, means for grading and distributing run of the mine coal thereto, a track lying parallel to and below the said row of bins, said track being adapted for the transportation of cars which are to be loaded from the said bins, a second track interposed between said first track and the outlet apertures of the bins, a loading machine adapted to travel upon said second track for positioning beneath any selected outlet aperture, a screen carried by the said machine and adapted to receive the gravity discharge of coal from said outlet aperture, means for moving said screen, means for discharging coal passing over the said screen into a car traveling upon the said first-named track, and separate means for discharging coal passing through the said screen, said last-named discharge means being directed laterally so that the issuing coal may fall clear of said first-named track and means to carry said rejected coal to where the run of the mine coal is received.

10. In coal-handling apparatus and, in combination, a plurality of bins mounted

in a single row and having elevated outlet apertures, means for grading and distributing run of the mine coal thereto, a track lying parallel to and below the said row of bins and adapted for the transportation of cars to be loaded from the said bins, a second track interposed between said first track and the outlet apertures of the row of bins, a loading machine adapted to travel on the second track for positioning beneath any selected outlet aperture, a screen carried by said loading machine and adapted to receive a gravity discharge of coal from the said outlet aperture, means for discharging coal passing over the said screen into a car traveling upon the first-named track, a conveyer system, a portion of which lies parallel to said first-named track and which ultimately discharges into said bins, and a laterally directed discharge means carried by said loading machine and receiving coal which passes through the said screen and directing the same onto the said conveyer system.

11. A loading machine comprising a frame, supporting wheels carried by said frame, an inclined screen mounted for reciprocation on the frame, means for reciprocating said screen, means for discharging material passing over said screen longitudinally of the machine, and means for discharging material passing through the said screen laterally of the machine, in combination with traveling conveyers adjacent both of the discharge outlets.

12. In a loading machine and, in combination, a frame, supporting wheels carried by the frame, an inclined screen mounted for reciprocation on the frame, means for reciprocating the screen, means for discharging material passing over the screen longitudinally of the machine, and a conveyer mounted transversely of the machine for discharging material passing through the screen laterally of the machine, in combination with traveling conveyers adjacent both of the discharge outlets.

13. In a loading machine and, in combination, a frame, supporting wheels carried by the frame, a screen carried by the frame and inclining toward one end of the same, means for reciprocating the screen to feed material downwardly along the same and discharge it from the lower end thereof, and means for discharging material passing through the screen laterally of the machine, in combination with traveling conveyers adjacent both of the discharge outlets.

14. In a loading machine and, in combination, a frame, supporting wheels carried by the frame, a screen mounted on the frame and inclining toward one end thereof, means for reciprocating the screen to cause material to pass downwardly over the

- same and to discharge from the lower end thereof, and a conveyer mounted transversely of the machine and below said screen to receive material passing through the same and discharge it laterally of the machine, in combination with traveling conveyers adjacent both of the discharge outlets.
15. In a loading machine and, in combination, a frame, supporting wheels carried by the frame, a reciprocating screen mounted upon the frame, a reciprocating counterbalance weight connected with the said screen to move oppositely thereto, means for discharging material passing over the screen, and means for separately discharging material passing through the screen.
16. In a loading machine and, in combination, a frame, supporting wheels carried by the frame, an inclined reciprocating screen mounted upon the said frame, an eccentric shaft, a connecting rod operable from the said shaft and secured to the said screen, a second connecting rod operable from said shaft and angularly displaced 25 180° with relation to said first connecting rod, a reciprocating counterbalance weight driven from said second connecting rod, means for discharging material passing over said screen, and means for separately discharging material passing through the screen.
17. In a loading machine and, in combination, a frame, supporting wheels carried by said frame, resilient vertical supports fixed to the said frame at their lower ends, a screen carried by the upper ends of said supports, an eccentric shaft, a connecting rod operable from the said shaft and secured to the said screen for reciprocating the latter, 35 a second connecting rod operable from the said shaft and angularly displaced 180° away from said first connecting rod, a rolling counterbalance weight connected with the free end of said second connecting rod, means for discharging material passing over the screen, and means for separately discharging material passing through the screen.
18. In a loading machine and, in combination, a frame, supporting wheels carried by the frame, vertical resilient supports fixed to the said frame at their lower ends, a screen carried by the upper ends of said supports and inclined longitudinally of the frame, an eccentric shaft mounted transversely of the frame, a connecting rod operable from said shaft and adapted to reciprocate the said screen in the direction of its inclination, a second connecting rod operable from the said shaft and angularly dis-
- placed 180° with relation to said first connecting rod, a counterbalance roll carried by the free end of said second connecting rod, and means for discharging material passing through the screen laterally of the 65 said frame.
19. In a loading machine and, in combination, a frame, supporting wheels carried by the frame, vertical resilient supports fixed to the said frame at their lower ends, 70 an inclined screen carried by the upper ends of said supports longitudinally of the frame, an eccentric shaft, a resilient connecting rod operable from the said shaft and rigidly fixed at its free end to the said screen, means for longitudinally discharging material passing over the screen, and means for laterally discharging material passing through the screen, in combination with traveling conveyers adjacent both of 75 the discharge outlets.
20. In a loading machine and, in combination, a frame, supporting wheels carried by the frame, vertical resilient supports fixed to the said frame at their lower ends, 80 an inclined screen carried by the upper ends of the said supports and having screen sections the mesh of which is progressively less toward the lower end of the screen, means for reciprocating said screen to cause material to pass downwardly over the screen and discharge from the lower end thereof, and means for separately discharging material passing through the screen.
21. In a loading machine and, in combination, a frame, supporting wheels carried by the frame, vertical resilient supports secured to the said frame at their lower ends, a screen carried by the upper ends of said supports and inclining longitudinally of the 95 frame, an eccentric shaft mounted transversely of the frame, a pair of resilient connecting rods operable from the said shaft and having their outer ends rigidly fixed to the said screen, a second pair of connecting rods operable from the said shaft and angularly displaced 180° with relation to said first pair of connecting rods, a counterbalance roll mounted to reciprocate parallel to the said screen, connections between said 100 counterbalance roll and said second pair of connecting rods, and a conveyer mounted transversely of the said frame and below the said screen to receive material passing through the screen and discharge it laterally 105 of the said frame.

DE WITT W. BUCHANAN.

In presence of—
 A. H. FLANIGAN,
 GUY N. ST. CLAIR.
